DESIGN FOR A DRESS

Anne Rebuhn, New York, N. Y.

Application February 12, 1940, Serial No. 90,197

Term of patent 3½ years

To all whom it may concern:

Be it known that I, Anne Rebuhn, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof.

The characteristic feature of my design resides in the specific combination on the specific dress disclosed of the metal button trimming arranged around the neck, down the front of the blouse portion, and on the belt as shown.

I claim:

The ornamental design for a dress, substantially as shown and described.

ANNE REBUHN.
